United States Patent Office.

WILLIAM H. LEACH, OF UXBRIDGE, MASSACHUSETTS, ASSIGNOR TO BRADFORD STETSON, OF SAME PLACE.

Letters Patent No. 79,360, dated June 30, 1868.

IMPROVED MACHINE FOR ROLLING LEATHER.

The Schedule referred to in these Letters Patent and making part of the same.

Be it known that I, WILLIAM H. LEACH, of Uxbridge, in the county of Worcester, and State of Massachusetts, have invented a new and useful Improvement in Machines for Rolling Leather, of which the following is a full, clear, and exact description, reference being had to the accompanying drawings, making a part of this specification, in which—

Figure 1 represents a rear elevation of a machine embodying my improvements.

Figure 2 is a side elevation,

Figure 3 is a transverse vertical section, and

Figures 4, 5, and 6, are details of portions of the machine.

Similar letters indicate like parts in the several figures.

The object of my invention is to provide a means for exerting an increased amount of pressure upon leather as it is passed between the rolls in a machine for rolling leather; and the invention consists in mounting the journals of the lower or pressure-roller in a movable-lever frame, which latter is provided with projections on the under side of either end, that rest upon arms or joints, and which joints are supported upon the central portion of a cross-piece in the main frame, in such a manner as to operate with the lever-frame like a toggle-joint, in addition to the usual compound lever employed for elevating or moving the pressure-roller.

Referring to the drawings, A represents the frame of a machine, which may be of any suitable form or size. B B' are the rollers, between which the leather to be rolled is passed. The upper roller B is journaled in the upper portion of the frame A, and has only a rotating motion. The journals of the lower roller B' rest upon projections b b of a lever-frame, C C', of the form shown in figs. 4 and 5, and they are also fitted to slide in vertical slots on each side of the frame directly under the journals of the upper roller B. The portion C' of the lower frame extends to the rear of the machine, as shown in fig. 3, and is connected, by means of the rod D, to the treadle-lever T. S. is a spring, that holds the treadle in an elevated position. These parts are of the ordinary construction, and operate in a well-known manner.

On the under side of the portion C of the lever-frame, at each side, are projections, e, which extend downwards and rest upon arms or joints E, supported upon a cross-piece, F, of the frame on each side. The projections e and the joints or arms F are so arranged as to act as toggle-joints, so that upon depressing the lever-frame C' the arm or joint F will be brought forward, and thus raise the bearings b that support the journals of the roller B', thus pressing the latter upwards with great force against the leather or other substance between the rollers.

On the outer ends of the bearings b of the lever-frame C C' are flanges, d d, which are designed to fit snugly on the outer sides of the frame, and thus hold the two sides of the frame together.

By means of the above-described construction and arrangement of parts, I am enabled, by the exercise of very little power comparatively, to exert a very great pressure upon the leather or other material operated upon, thus very greatly increasing the efficiency of this class of machines.

Having thus described my invention, what I claim as new, and desire to secure by Letters Patent, is—

1. The arrangement of the lever-frame C, provided with the projections e, and the compound lever C' D T, when the parts are constructed and made to operate the roller B', as and for the purpose set forth.
2. The flanges d d on the bearings b of the lever-frame C, as and for the purpose set forth.

In testimony whereof, I have signed my name to this specification in the presence of two subscribing witnesses.

WM. H. LEACH.
